UNITED STATES PATENT OFFICE.

NATHAN C. JOHNSON, OF ENGLEWOOD, NEW JERSEY, ASSIGNOR TO RAYMOND CONCRETE PILE COMPANY, OF NEW YORK, N. Y., A CORPORATION OF NEW JERSEY.

ART OF APPLYING REINFORCEMENT TO CONCRETE-PILE SHELLS AND THE LIKE.

1,206,541.

Specification of Letters Patent. Patented Nov. 28, 1916.

Application filed June 4, 1915. Serial No. 32,174.

To all whom it may concern:

Be it known that I, NATHAN C. JOHNSON, a citizen of the United States of America, and a resident of Englewood, county of Bergen, and State of New Jersey, have invented Improvements in the Art of Applying Reinforcement to Concrete-Piling Shells and the like, of which the following is a specification.

10 My invention relates to improvements in the art of applying reinforcement to concrete piling shells and the like, and consists in applying the reinforcement, preferably in the form of a helically wound coil, to an 15 expansible mandrel, inserting this mandrel in a suitable casing, and expanding the mandrel to cause same to grip the coil, driving the casing, with the mandrel within it, into the ground, and causing the laterally-exerted earth pressure of the ground then surrounding such casing to press the casing inward around the reinforcement and thereby to interlock the casing with such reinforcement.

25 At the present day it is the practice to form reinforced piling-shells in the shop by placing a helically wound reinforcing rod or wire either within or without a suitable casing (the wire coil being usually placed 30 within the casing) and then by elaborate and expensive machinery beading the casing so as to cause the same to interlock with the reinforcing coil. This present day method has the great objections that the 35 work must be done in the shop, and the finished casings shipped to the point of use; whereas if the sheets from which the casings are to be formed can be shipped flat to the point of use, and the reinforcing wire 40 shipped in coils to the point of use, and the casing formed and the reinforcing coil inserted at the point of use, (as may be done according to my invention) shipping costs are very greatly reduced, also the use of the 45 elaborate and expensive beading machinery heretofore referred to, is avoided.

I will now proceed to describe my invention with reference to the accompanying drawings, and will then point out the novel 50 features in claims.

In said drawings, Figure 1 shows an elevation of a driving mandrel such as may be used for driving piling shells, with a reinforcing coil therearound, and shows in central vertical section the piling shell sur-

rounding that mandrel and reinforcing coil. Fig. 2 is a similar view showing the shell partly driven into the earth and showing how, by the pressure exerted by the earth, the shell is pressed inward so as to interlock with the reinforcing coil. Fig. 3 is a detail view on a larger scale, showing in section the interlocking of the shell with the reinforcing coil.

In the drawings numerals 1, 1, designate 65 segment leaves of a mandrel, 2 designates a central spindle of the mandrel, 3 designates a driving head for the mandrel, and 4, 4 designate toggle levers connecting the spindle 2 with the segmental leaves 1. The 70 particular construction of this mandrel is unimportant for present purposes, since other well known mandrels may be used; and moreover the particular mandrel shown forms the subject matter of a separate application for Letters Patent filed June 4, 1915, Serial No. 32,173. In general, it may be understood that the mandrel is one of such nature that downward motion of the 75 spindle 2 with reference to the leaves 1 80 forces these leaves outward.

5 designates the shell or casing, and 6 a helically wound reinforcement.

7 designates a bottom piece or point, either separable from or attached to the 85 mandrel itself, as may be desired.

In practising my invention the reinforcing coil is preferably drawn over the mandrel which may be either in its collapsed or in its expanded position. It is advantageous 90 in many ways, however, to draw the wound reinforcement over the mandrel when in collapsed position, expanding the mandrel in such manner as to tightly bind the reinforcement against the outside of the mandrel 95 leaves. Also, either before or after the expansion of the mandrel and after drawing the reinforcement over the mandrel the shell or casing is placed outside of the mandrel and also outside of the reinforcement. If 100 this is done prior to the expansion of the mandrel such expansion is brought about by usual methods. In any event, after placing shell and reinforcement in proper position on the mandrel whether this is done prior to 105 or after the expansion of the mandrel the expanded mandrel with the assembled reinforcement and casing is driven into the ground by proper means such as a drop hammer or other types of hammer com- 110

monly employed in the art of driving piles. As the mandrel with its end casing shell is forced down into the earth the earth pressure, exerted laterally upon the shell, forces 5 that shell inward against and around the reinforcing coil 6, forming a helical bead 8 on such shell, as clearly shown in Figs. 2 and 3. The earth pressure thus exerted is often times very great indeed; so much so that but 10 for the reinforcing coil the shell would collapse immediately upon withdrawal of the mandrel; and such pressure is therefore ample sufficient to force in the metal of the shell around the reinforcement, as shown. 15 After the casing has been driven, the mandrel is withdrawn, the collapsibility of the mandrel being such that when the stem 2 is drawn upward the leaves 1 of the mandrel are drawn in clear of the reinforcement, and 20 then the shell may be filled with liquid concrete; or if preferred, the liquid concrete may be poured in while the mandrel is in place, and the mandrel withdrawn before the concrete has set; the latter method having 25 the advantage that the weight of the concrete will guard against any possibility of the shell being forced inward or upward by the pressure exerted upon it.

While I have illustrated my invention as 30 applied to tapering shells, it obviously is equally applicable to straight cylindrical shells, the action involved in uniting the shell to the reinforcement, being the same, whether the shell be cylindrical or tapering.

35 What I claim is:—

1. The herein described improvement in the art of applying reinforcement to concrete piling shells and the like, which consists in driving a shell of material yieldable 40 under earth pressure, each shell having supporting reinforcement within it, into the ground, and by the laterally exerted earth pressure pressing the casing in around the reinforcement, and thereby causing the casing to unite with the reinforcement.

45 2. The herein described improvement in the art of applying reinforcement to con-

crete piling shells and the like, which consists in driving a shell of material yieldable under earth pressure, each shell having supporting reinforcement within it, into the ground, and by the laterally exerted earth pressure forming in the casing a bead receiving and in part surrounding the reinforcement. 50

55 3. The herein described improvement in the art of applying reinforcement to concrete piling shells and the like, which consists in placing around reinforcement a shell of material yieldable under earth pressure, 60 placing an expansible mandrel within the shell and reinforcement, and expanding the mandrel and so holding the reinforcement against the shell, driving the shell, with the reinforcement and mandrel within it, into the ground, and by the laterally exerted earth pressure pressing the shell inward and around the reinforcement, and thereby uniting the reinforcement with said shell, and then collapsing and withdrawing the mandrel. 65

70 4. The herein described improvement in the art of applying reinforcement to concrete piling shells and the like, which consists in placing around a helically wound reinforcement coil a shell of material yieldable under earth pressure, placing an expansible mandrel within that coil, and expanding the mandrel and so holding the reinforcement against the shell, driving the shell, with the reinforcement and mandrel within it, into the ground, and by the laterally exerted earth pressure pressing the shell inward and around the reinforcement, and thereby uniting the reinforcement with said shell, and then collapsing and withdrawing the mandrel. 75

80 In testimony whereof I have signed this specification in the presence of two subscribing witnesses.

NATHAN C. JOHNSON.
